LUBRICATING MEANS FOR SEWING MACHINES

Otto R. Haas, North Beverly, Mass., assignor to
United Shoe Machinery Corporation, Borough
of Flemington, N. J., a corporation of New
Jersey

Original application April 29, 1936, Serial No.
76,924. Divided and this application April 6,
1938, Serial No. 200,410

17 Claims. (Cl. 112—256)

The present invention relates to sewing machines, and more particularly to a lubricating system for shoe sewing machines and the like. The invention is herein disclosed as embodied in 5 a lockstitch outsole shoe sewing machine forming the subject-matter of application Serial No. 76,924, filed April 29, 1936, the present application being a division of said case.

Due to the relatively high speed of operation 10 of the shoe sewing machine disclosed in said application, it is essential that all moving parts of the machine be adequately lubricated.

The proper lubrication of a high speed shoe sewing machine, and more particularly of the 15 various stitch-forming devices adjacent the sewing point as, for example, the needle, the needle supporting stud, and the shuttle or loop taker of a lockstitch outsole shoe sewing machine is rendered difficult by the fact that if lubricant is supplied to these parts in adequate quantities to insure proper lubrication, there is great likelihood 20 of soiling the work as a result of excess lubricant leaking from the bearing surfaces, not only when the machine is running, but also after the machine 25 has come to a stop.

It is, therefore, the object of the present invention to provide a new and improved system of lubrication for shoe sewing machines which will automatically insure a supply of lubricant in ample quantities to all moving parts of the machine 30 during the operation thereof without risk of the lubricant reaching the work.

With this object in view, features of the present invention contemplate new and improved means for providing a continuous supply of lubricant 35 to the stitch forming devices of a shoe sewing machine, and more particularly to the bearings of the curved hook needle and to the needle itself and needle guide of such a machine, and to the bearing of the shuttle or loop taker of a lockstitch shoe sewing machine.

Another feature of the invention includes means for automatically cutting off the supply of oil to certain of the parts upon stopping the machine.

These and other features of the invention including certain novel and improved constructions and arrangements of parts are herein described in the following specification and illustrated in the accompanying drawings, in which 50 Figure 1 is a view in side elevation, looking from the right, of a lockstitch shoe sewing machine embodying the features of the present invention; Figure 2 is a plan view of the head portion of 55 the machine illustrated in Figure 1, with the

covers removed and other parts broken away to show the oil distributing manifolds and certain of the oil supply pipes; Figure 3 is a sectional view in right hand side elevation of the machine head, illustrating a number of the actuating 5 mechanisms for the stitch forming devices; Figure 4 is a view in right side elevation and in section, illustrating the shuttle and its oil collecting guard; Figure 5 is a plan view of the shuttle, illustrating the lubricating fluid inlet; Figure 6 is a view in front elevation, partly in section, and on an enlarged scale, of the needle supporting stud and surrounding portions of the machine; Figure 7 is a detail sectional view of the needle and awl carrier stud; Figure 8 is an enlarged 10 sectional view of the needle guide and a portion of the needle stud, showing the oil passage for lubricating the needle; Figure 9 is an enlarged detail view of the needle guide and stud, the stud being shown in section; Figure 10 is a detail sectional view, taken along the line 10—10 of Figure 7, the parts being shown in the 15 position they assume when the machine is stopped; and Figure 11 is a view similar to Figure 10, but with the parts shown in a running 20 position.

The machine illustrated in the drawings, and in which the present invention is embodied, is a high speed manually controlled wax thread shoe sewing machine of the type employed to sew 25 the outsole to a welted upper. The head frame, indicated at 12, includes the stitch forming devices and their actuating mechanisms and is supported on a vertical pedestal 14 secured to a base 16. A driving motor 18 secured to the base 16 30 operates to rotate the main sewing shaft 20 of the machine in clockwise direction through a belt 22 and a driving pulley 24 of the driving and stopping mechanism, which mechanism is substantially the same as that illustrated and described in the present inventor's U. S. Patent No. 2,078,942 of May 4, 1937. A foot-operated treadle 26 controls the operation of the driving and stopping mechanism through a treadle rod 28.

The stitch forming and work feeding devices 45 of the machine include a curved hook needle 30, a curved awl 32, a needle guide 34, a shuttle or loop taker 36 within a guideway of which is mounted a hollow circular thread case 38, a looper 40, a loop spreader 42, a thread hook or 50 finger 44, a take-up 46, a presser-foot 50 and a work support 52. The stitch forming and work feeding devices are actuated to sew a seam while advancing the work continuously by alternating feeding movements of the presser foot and work 55

support as a unit while the work is clamped, and of the needle and awl as a unit when the presser foot is raised from the work. Certain of the devices are actuated by trains of mechanism from 5 cam discs on the main sewing cam shaft 20, while other devices are driven by connections from cam discs mounted on a supplementary cam shaft 54 at the rear of the shaft 20 and rotated therefrom by intermeshing gearing, (see 10 Fig. 1). A number of the actuating mechanisms for the stitch forming devices are illustrated in Fig. 3, the cam levers for oscillating the needle 30 and awl 32 being indicated at 56 and 58 respectively. The cam-actuated lever for the loop 15 spreader is shown at 60, while the lever for imparting the in-and-out motion to the looper is indicated at 62. The take-up is actuated by cam lever 64, and the cam-actuated lever for raising and lowering the presser foot is indicated at 66. 20 For a more complete description of the various actuating mechanisms, reference may be had to application Serial No. 76,924 above referred to.

Due to the relatively high speed at which the present machine is designed to be operated, the 25 lubricating system is arranged to supply oil automatically to all bearing surfaces whenever the machine is in operation. To catch the oil thrown off by the cams and other moving parts and to enable the oil to be recirculated, the head frame 30 of the machine is entirely enclosed by oil retaining covers except for suitably shaped openings for the stitch forming and work feeding devices. The frame is so arranged that all the oil collected by the covers is drained into a common 35 reservoir or sump 68 located within a downwardly projecting cylindrical member 70 which forms a portion of the head frame 12 of the machine. To permit the machine head to be raised or lowered as required for the convenience 40 of the operator, the cylindrical member 70 is received for vertical sliding movement in the upper end of the pedestal 14, the pedestal being slotted and provided with bolts 72 by which the member 70 may be clamped in adjusted position. 45 The machine is provided with a rotary pump 74 located at the rear of the machine (see Fig. 2) and driven continuously while the machine is in operation by the supplementary cam shaft 54. Oil is drawn from the sump 68 through a pipe 50 76 up to the pump 74 from which the oil is supplied under pressure through a pipe 78 to a horizontally elongated manifold 80 mounted at the upper rear portion of the machine frame substantially parallel to the cam shaft 20. A 55 second manifold 82 is provided at the front upper portion of the machine and is supplied with oil from the manifold 80 through a pipe 83. The manifold 82 is fan-shaped, having radially disposed outlets. 60 From the manifolds the oil is distributed to the various operating parts of the machine, the horizontally extending manifold 80 supplying through tubes 84 those bearings and parts which are arranged more or less in line, namely, the 65 sewing cam shaft 20, the cams, cam levers, etc., while the fan-shaped manifold 82 supplies oil to the stitch-forming devices, which are grouped in a unit or cluster at the front of the machine. The lubricant is applied to the bearing surfaces 70 in various ways, in certain instances the oil being sprayed through reduced orifices onto the operating parts, and in others the flow of oil is limited to approximate the requirements of the parts to be lubricated. The construction and operation 75 of the oiling means for the driving and stopping

mechanism is fully illustrated and described in the inventor's U. S. Patent No. 2,078,942 above referred to.

To prevent the oil thrown off by the cams on the main sewing shaft from reaching the 5 work operated upon, there is provided a baffle plate 85 (see Fig. 3) extending across the front of the machine between the needle and awl stud, and the connections for operating the needle and awl. To prevent the oil deflected by the 10 baffle plate from dripping onto the operating connections at the upper edge of the opening through which the connections pass, there is secured to the lower edge of the plate a semi-circular oil conducting trough or channel 86. 15 The channel piece 86 extends downwardly at either side of the opening to collect and conduct the oil intercepted by the baffle plate into the machine frame, where it flows rearwardly into the sump 68. 20

To lubricate the shuttle and thread case, the manifold 82 is connected with a tube 88 (Figs. 2 and 5) which carries oil to the upper surface 89 of the guideway for the shuttle. Along the tube 88 close to the manifold 82 is connected a 25 flow restricting orifice member 90. From the guideway surface 89 oil is conducted to the guideway 91 for the thread case through a passage 92. Any additional oil which collects on the thread case or the shuttle is carried by 30 gravity into an upwardly curved concave metal guard 93 (see Fig. 4) surrounding the lower part of the shuttle. The guard 93 is of the proper shape to deflect each needle loop passed about the thread case and prevent the thread from 35 being whipped against the surface of the work operated upon, as frequently occurs as a result of the motion imparted to the loop when cast off by the shuttle. The guard 93 serves to retain the needle loop, after being cast off by the shuttle, until the thread is pulled free by the action of the take-up, with the result that whipping of the needle loop is substantially eliminated. At the right end of the guard there is formed an open rearwardly extending trough portion 94 40 for conducting excess oil rearwardly away from the shuttle and thread case, and arranged to discharge the oil within one of the covers of the main frame. 45

The needle and awl supporting stud, indicated 50 at 96 (see Figs. 6 to 11) is formed with a central oil conducting passage 98, the open end of which is closed by a nut 100. The stud is constructed in substantially the same manner, except for the lubricating passage, as in the machine of 55 inventor's Patent No. 2,037,721 of April 21, 1936, one end of the stud being supported in a plain bearing 102 secured to the machine frame while the other end is received in a threaded bearing 104 mounted on the feed carriage 106 of the 60 machine. Surrounding the stud 96 and operating as a unit therewith is a sleeve 108 provided with a gear segment 110 by which the stud is oscillated to reciprocate the needle and awl in the line of feed. 65

To supply oil to the passage 98 in the stud, the stud 96 and sleeve 108 are provided with a radial opening 111 at their right hand end. A sleeve portion 112 of the awl carrying segment 114 surrounds the stud 96 within the bearing 70 102 and is likewise provided with a radial opening 116. These openings are arranged to be in alignment at certain times in the machine cycle with an oil passage 118 formed in the bearing 102 for the right hand end of the stud, as shown in 75

Fig. 11. The passage 118 extends from the outlet rearwardly through the bearing 102 to the point of attachment of the bearing on the machine frame (see Fig. 7) where it joins a passage 120 in the frame 12 connected to the oil distributing manifold 82 by a tube 122. A flow-limiting orifice 124 between the tube and the manifold serves to restrict the flow of oil under pressure to a few drops per minute. A part of the oil supplied through the passage in bearing 102 is conducted along the passage 98 in the stud and through a radial opening 126 at the left end thereof to lubricate the threaded bearing 104 carried by the feed carriage. Any surplus oil not consumed in lubricating the bearing surfaces may run down the underside of the bearings 102 and 104 rearwardly towards the main frame 12 of the machine.

To receive the surplus oil from the bearing 102, there is disposed beneath the same a forwardly projecting flange 128 (see Fig. 3) forming a portion of the machine frame. The flange is inclined downwardly to the rear so that any oil deposited on its upper surface flows back into the machine frame and returns to the sump 68.

The bearing 104 for the left end of the needle and awl stud 96 is arranged just above a guideway 130 between parallel guiding surfaces of which a rod 132 carrying the looper 40 is slidably mounted. The lower forward edge of the guideway surface projects beyond the upper surface and is provided with an oil receiving groove 134 within which surplus oil from the guideway surfaces may be caught. The groove 134 is so arranged that oil dripping from the bearing 104 will fall on and lubricate the looper carrier rod 132, any excess oil being collected in the groove 134 and thence conducted back into the machine frame.

40 To enable the needle to be lubricated, a sleeve portion 136 of the needle segment, indicated at 138, is formed with a radial passage 140 (Fig. 8) brought into alignment at certain times during operation of the machine with a radial opening 142 in the stud 96. The needle guide 34 which surrounds the hub of the needle segment is provided with a circumferential groove 144 around its inner bearing surface. The groove 144 registers with the outer end of radial passage 140 in the 45 needle stud, and is connected with an outwardly directed passage 146 in the main body of the needle guide 34. At its outermost end, the passage 146 bends at an angle and follows the contour of the needle guide to its tip. The opening 50 at the end of the passage 146 is closed by the side of the needle, and any oil finding its way through the passage of the needle guide is brought into contact with the needle so as to be distributed along the bearing surfaces between 55 the needle and the needle guide.

60 When the machine is brought to rest by the driving and stopping mechanism, it is desirable that the supply of oil be cut off from the needle and awl stud so that there will be no accumulation 65 on the stitch-forming devices. Accordingly, the openings 111 and 116 in the stud and awl segment are so arranged that they will not register with each other when the machine is stopped, as shown in Fig. 10. As a further precaution 70 the outer bearing surface of the awl segment sleeve 112 is formed with a by-pass groove 148 which, when the machine is stopped, registers at one end with an opening 150 provided at the side of the bearing in such relation that the oil forced through the groove will be carried along 75

the surface of the bearing 102 and back to the main frame in a manner previously described. The by-pass groove 148 prevents a pressure from being built up in tube 122 and passage 118 while the machine is stopped so that when the machine is restarted the parts will not suddenly be flushed with oil.

In order to provide a more accurate shape for the needle guiding opening of the needle guide 34, and to simplify the construction of the oil passage therein, the outer tip of the needle guide is made separate from the main body portion thereof. Due to difficulties in forming accurately a curved hole which will fit the shape of the needle, the outer tip, indicated at 152, of the needle guide is formed in a mold, either of metal or synthetic resinous material and is secured to the main body portion by means of dowel pins 154 and a small screw 156. Molding materials of the synthetic resin type ordinarily are not of sufficient strength and rigidity to provide adequate support for the needle, but by forming the main body of the needle guide 34 of steel, suitable reinforcement is provided to withstand the ordinary strains imparted during sewing.

In order not to block the free movement of oil through the passage 146 in the needle guide, the inner surface of the main body portion of the needle guide which registers with the surface of the separate tip 152 is counter-bored around the screw 156, as indicated in Figure 9, the oil passing freely through the circular channel thus formed. A part of the passage 146 is formed in the separate tip 152 of the needle guide, so that when clamped in overlapping relation by the screw 156 no break in the continuity of the passage 146 will occur.

The nature and scope of the present invention having been indicated, and a specific embodiment thereof having been illustrated and described, what is claimed is:

1. A sewing machine having, in combination, stitch forming devices comprising a rotary loop taker disposed above the work being operated upon, a bearing for the loop taker, actuating mechanisms for said devices, an oil retaining casing surrounding said mechanisms, means for providing a continuous supply of lubricating oil to the loop taker bearing, and a loop deflector surrounding the loop taker and having a cavity to conduct surplus oil from the bearing back into the oil retaining casing.

2. A sewing machine having, in combination, a main sewing shaft, thread manipulating and stitch forming devices at the front and to one side of the sewing shaft, actuating mechanisms for said devices driven from the sewing shaft, an oil retaining casing surrounding the sewing shaft and said mechanisms, means for providing a continuous supply of lubricant to the actuating mechanisms, and a baffle plate disposed between the sewing shaft and said devices to conduct oil thrown off centrifugally from the sewing shaft back to the oil retaining casing.

3. A sewing machine having, in combination, stitch forming devices comprising a curved needle, a hollow oscillatory needle supporting stud, and stud supporting bearings, one of which is provided with means for supplying oil through the stud to lubricate the other bearing.

4. A sewing machine having, in combination, stitch forming devices comprising a curved needle, actuating mechanisms for said devices, an oil retaining casing surrounding said mechanisms, a hollow oscillatory needle stud, stud supported

- bearings, one of which is provided with a passage for supplying oil through the stud to lubricate the other, and means for draining the surplus oil from said bearings back into the oil retaining 5 casing.
5. A sewing machine having, in combination, stitch forming devices comprising a curved hook needle and a looper, actuating mechanisms for said devices, an oil retaining casing surrounding 10 said mechanisms, an oscillatory needle stud, stud supporting bearings, and a looper supporting bearing disposed to receive surplus oil from one of said needle stud bearings and drain it back into the oil retaining casing.
15. 6. A sewing machine having, in combination, stitch forming devices comprising a curved needle, a hollow oscillatory needle supporting stud having radial openings therein, a stud supporting bearing provided with an oil discharging 20 opening arranged to register with a radial opening in the needle stud in one oscillatory position of said stud, and a driving and stopping mechanism for bringing the stitch forming devices to rest with said radial opening in the needle stud 25 out of registry with the oil opening in said bearing to prevent the flow of oil from the oil opening to the radial opening.
7. A sewing machine having, in combination, stitch forming devices comprising a curved needle, a hollow oscillatory needle supporting stud having radial openings therein, a stud supporting bearing provided with an oil discharging 30 opening arranged to register with a radial opening in the needle stud in one oscillatory position 35 of said stud, means for supplying a restricted quantity of oil under pressure to said oil opening, and means rendered effective when the machine is stopped to by-pass the oil in the oil opening before it enters the stud.
40. 8. A sewing machine having, in combination, stitch forming devices comprising a curved needle, a hollow oscillatory needle supporting stud having radial openings therein, a stud supporting bearing provided with an oil discharging 45 opening arranged to register with a radial opening in the needle stud in one oscillatory position of said stud, means for supplying a restricted quantity of oil under pressure to said oil opening, and a sleeve between the stud and said 50 bearing formed with a by-pass groove to relieve the pressure of the oil in the oil opening when the sleeve is moved to a predetermined position.
9. A sewing machine having, in combination, stitch forming devices comprising a curved needle 55 and a curved awl, segments to which the needle and awl are secured, a needle and awl supporting stud, a stud supporting bearing provided with an oil discharging opening, and means comprising a portion of one of said segments formed 60 with a by-pass to relieve the pressure in the oil discharging opening when the stitch forming devices are in predetermined positions.
10. A sewing machine having, in combination, stitch forming devices comprising a curved work 65 penetrating needle, and means for directing fluid against the needle comprising a needle guide having a fluid receiving passage arranged at one end to be covered by the side of the needle.
11. A sewing machine having, in combination, 70 stitch forming devices comprising a curved work penetrating needle, means for supplying lubri-
- cant under pressure to the needle comprising a needle guide having a passage arranged at one end to be covered by the side of the needle, a flow-limiting orifice for restricting the quantity of lubricant supplied to the needle guide passage, and cut-off means between the orifice and the needle guide passage to prevent an accumulation of lubricant on the needle.
12. A sewing machine having, in combination, 10 stitch forming devices comprising a curved work penetrating needle, a bearing stud having an outlet along its bearing surface for a supply of fluid under pressure, a needle guide supported on said bearing stud having a passage arranged at one end to receive fluid from said outlet and 15 at the other end to be closed by the side of the needle.
13. A sewing machine having, in combination, 20 stitch forming devices comprising a curved work penetrating needle, means for supplying lubricant under pressure to the needle comprising a needle guide having a passage arranged at one end to be covered by the needle, a lubricant conducting tube having a restriction to limit the quantity of oil supplied to the needle guide passage, and means for by-passing the lubricant between the needle guide and the restriction in 25 the conducting tube when the machine is stopped.
14. A sewing machine having, in combination, 30 stitch forming devices comprising a curved work penetrating needle, and a guide member constructed in two parts secured together, one of said parts being formed by molding while in a plastic condition with a curved needle guiding hole of exact size and lengthwise curvature to fit 35 the needle, and the other of said parts being formed of metal of sufficient strength to withstand the strains imparted by the needle during 40 sewing.
15. A sewing machine having, in combination, 40 stitch forming devices comprising a curved work penetrating needle, and a needle guide member constructed in two parts, one of which serves as a support arm and the other of which engages the needle, at least one of said parts being 45 grooved along a registering surface to form a fluid conducting passage from the support arm to the needle engaging part when clamped together in overlapping relation.
16. A shoe machine having, in combination, a 50 pedestal, a head above the pedestal having a vertical cylindrical portion at its lower part releasably clamped for suitable adjustment vertically within the pedestal, operating devices within the head, means for distributing lubricant in said 55 head, and a lubricant collecting sump within the cylindrical portion of the head.
17. A sewing machine having, in combination, 60 stitch forming devices comprising a curved work penetrating needle, means for supplying lubricant under pressure to the needle comprising a needle guide having a passage arranged at one end to be covered by the side of the needle, a flow-limiting orifice for restricting the quantity of lubricant supplied to the needle guide passage, and means between the orifice and the needle 65 guide passage actuated, when the machine is stopped, to cut off the supply of lubricant to said passage to prevent an accumulation of lubricant on the needle.
